COMBINED MAIL BOX, BELL, NUMBER AND NAME PLATE

Ralph E. Voepel, St. Louis County, Mo.

Application June 4, 1934, Serial No. 729,003

1 Claim. (Cl. 40—132)

This invention relates to letter or mail boxes for dwellings, and has for the primary object the provision of a device which will permit mail to be easily and quickly placed in or removed therefrom and also provides a mounting for a doorbell switch, house number and the name of the person residing in the dwelling or house and which may be efficiently illuminated so that from a distance and at night time the number of the dwelling and name of the occupant may be easily determined as well as permitting a caller at the dwelling to readily locate the doorbell switch or push-button.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a mail box constructed in accordance with my invention.

Figure 2 is a sectional view taken on the line 2—2 of Figure 1.

Figure 3 is a sectional view taken on the line 3—3 of Figure 1.

Figure 4 is a vertical sectional view illustrating a light compartment of the mail box and the means of supporting the illuminating lamp there-

in and taken on the line 4—4 of Figure 2.

Figure 5 is a fragmentary sectional view showing the mail compartment of the letter box.

Figure 6 is a plan view illustrating the follower and its connection to the cover of the mail box.

Figure 7 is a fragmentary sectional view showing the mounting of the name plate and character plate for the bell switch to the front wall of the mail box.

Figure 8 is a perspective view illustrating the character plate or panel for the switch.

Figure 9 is a fragmentary perspective view illustrating one of the number stenciled plates.

Referring in detail to the drawings, the numeral 1 indicates a casing adapted to be arranged vertically upon a support and includes a removable rear wall 2, projecting above and below the ends of the casing to form attaching portions or lips 3 apertured to receive fasteners to connect the casing to a support. The upper end of the casing is opened and closed by a hinged cover 4 and the latter is provided with a slot 5 to permit the insertion of letters or mail into the casing when the cover is in a closed position. The cover 4 is also provided with an opening 6 to receive a spring catch 7 carried by the casing and the latter

is apertured, as shown at 8, so that a shackle of a lock may be passed therethrough for securing the cover in a closed position.

The casing 1 is divided into mail and light compartments 9 and 10 by a heat resisting partition 11. The partition is mounted in grooves formed in opposite walls of the casing, as shown at 12. The bottom wall of the casing is provided with vent openings 13 to admit air to the light compartment 10 and the latter is illuminated by an electric lamp 14 carried by a socket 15 mounted in a spring clamp 16. The spring clamp has a shank 17 integral therewith and engages one face of the partition. The upper portion of the shank is bent to form a hook 18 that passes over the upper edge of the partition and grips the opposite face of the partition from that engaged by the shank 17. Thus the electric lamp is removably secured to the partition and will permit of the electric lamp being removed from the compartment when necessary. The conductors 19 of the electric lamp socket extend downwardly in the light chamber and pass outwardly of the casing by way of a tube 20. The conductors 19 form part of an electric circuit (not shown) and also arranged within the electric circuit is a doorbell controlled by a switch 21 of the push-button type. The push-button is mounted to the front wall of the casing and which will be hereinafter more fully described.

A follower plate 22 is slidably mounted in the mail compartment and is connected to the cover 4 by rods 23, the latter having their upper ends pivoted to the cover and their lower ends angularly related to underlie the follower plate. The cover 4 when swung to an open position will cause an upward movement of the follower plate and any letters or mail in the mail compartment will be partially elevated out of the casing so that they can be easily grasped by a person.

The rear wall 2 of the casing has formed upon its inner face an enlargement 24 provided with oppositely inclined faces 25. The purpose of the enlargement 24 and the inclined faces 25 is to cause the letters or mail to assume an inclined position, as shown in Figure 2, the upper ends of the letters resting against partition and the lower ends upon the follower plate 22 and in engagement with the rear wall 2.

The upper portion of the front wall of the casing is provided with a comparatively large opening closed by a semi-transparent panel 26 and arranged between the panel and the front wall of the casing are number bearing plates 27. The plates 27 are preferably of a stencil type so that

the light rays from the electric lamp passing through the panel 26 will illuminate the numbers. These numbers represent the number of the dwelling. The stencil or number plate may be constructed of any material suitable for the purpose and the upper edge of each plate is offset to form a flange 28 overlain by the lower edge of the adjacent plate and the flange 28 has struck therefrom tongues 29 cooperating with the flange 28 in retaining the plate in slightly overlapped relation and against separation.

5 The front wall of the casing below the numbers is provided with an elongated opening 30 and surrounding the opening is a removable frame 31. 10 Clamped between the frame and the front wall and spanning the opening 30 is a name plate 32 preferably of the stencil type and bears the name of the occupant of the dwelling.

15 The front wall below the opening 30 is formed 20 with a substantially U-shaped opening 33 defining a tongue 34 integral with the front wall and this tongue is apertured and has mounted therein the push-button or switch 21. Closing the opening 33 is a semi-transparent panel 35 bearing characters 25 spelling the word "Bell" so that a caller at the dwelling will have attention directed to the push-button or switch and obviate the caller experiencing difficulty in locating the switch or button at night time.

The tube 20 is preferably constructed of an insulating material obviating the possibility of the conductors becoming short circuited and arranged in the circuit of the electric lamp is a switch 36 mounted to the bottom wall of the casing whereby the circuit for the electric lamp can be opened and closed when desired.

15 Having described the invention, I claim:

A character display device comprising a casing supporting characters to be illuminated from the inside of said casing, a vertical partition arranged in said casing to form an article compartment and an illumination compartment positioned next to the characters, said partition having its upper edge below the top of the casing to permit rays of light 15 being directed into the article compartment, and said partition having a notch in its upper edge adjacent one corner thereof, and a hanger in the illumination compartment and including a shank having angularly disposed portions engaging with 20 the partition with one portion terminating substantially centrally of the partition and formed to provide a clamp for receiving an illuminating means and the other portion being bent to form a hook lying in the notch and gripping opposite 25 faces of said partition.

RALPH E. VOEPEL.
